AUTOMATIC SELF-CLOSING WINDOW
VENTILATOR

Edward C. Hassildine, Queens Village, N. Y.

Application April 6, 1938, Serial No. 200,352

7 Claims. (Cl. 98—1)

This invention relates to new and useful improvements in an automatic self-closing ventilator.

More specifically, the invention proposes the construction of an automatic self-closing window ventilator characterized by a frame for engagement into a window opening and provided with a panel hingedly supported thereon and resiliently urged into its closed position and held 10 in an open position against the action of said resilient means.

Another object of this invention is to provide a finger rigidly mounted with relation to said panel and which is provided with an enlarged 15 head in the form of a collar for engagement beneath a hook for holding the panel in the open position.

Still further it is proposed to characterize the hook by a portion which is adapted to extend 20 away from the portion beneath which said head engages, and to provide the same frame with a a clock mechanism of conventional construction of said hook for releasing said roller head to permit said panel to be closed.

25 A still further object of this invention is to provide the self-closing window ventilator with an adjustable mechanism for holding the panel open to various degrees and which may be released when it is desired to close the said panel.

30 For further comprehension of the invention and of the objects and advantages thereof, reference will be had to the following description and accompanying drawings, and to the appended claims in which the various novel features of 35 the invention are more particularly set forth.

In the accompanying drawings forming a material part of this disclosure:

Fig. 1 is an inside elevational view of a window having an automatic self-closing window 40 ventilator according to this invention positioned therein.

Fig. 2 is a sectional view on the line 2—2 of Fig. 1.

Fig. 3 is a view looking in the direction of the 45 line 3—3 of Fig. 2.

Fig. 4 is an enlarged detailed view of a portion of Fig. 1.

Fig. 5 is a sectional view on the line 5—5 of Fig. 4.

50 Fig. 6 is a sectional view on the line 6—6 of Fig. 4.

Fig. 7 is a view similar to Fig. 6 but illustrating a different position of the parts.

55 Fig. 8 is a perspective view of a portion of the device.

Fig. 9 is a view similar to Fig. 7 but illustrating a modification of the invention.

Fig. 10 is a view similar to Fig. 9 illustrating a further position of the parts.

Fig. 11 is a sectional view taken on the line 11—11 of Fig. 9.

Fig. 12 is a view looking in the direction of the line 12—12 of Fig. 9.

Fig. 13 is a view similar to Fig. 12 but illustrating a still further position of the parts.

The automatic self-closing window ventilator includes a frame 10 for engagement under a window opening. The frame 10 is constructed of wood or other material and is adapted to be at the window frame and held in position by suitable 15 brackets 10' at one end of the window 11.

A panel is hingedly mounted at its bottom edge on the frame 10 and is capable of extending across the frame for closing the same. The panel comprises a wooden frame 12 which has a pane 20 of glass 13 fixedly mounted therein. The bottom edge of the panel frame 12 is hingedly supported upon a portion of the frame 10 by means of hinges 14. The panel is adapted to be extended to the position illustrated by the full lines in Figs. 2 and 7 for permitting air to pass through the opening in the frame to the inside of the room. The panel is also capable of being moved to the position illustrated by the dot and dash lines in Fig. 7, or the full lines in Fig. 6 to 30 close the opening in the frame 10 when so desired.

A pair of links 15 are pivotally connected together at their inner ends and pivotally connected at their outer ends to said panel and the frame 10, respectively, and adapted to fold to a closed position when the panel closes said frame.

The links 15 comprise separate pieces of metal 15^a and 15^b which are pivotally connected together at their inner ends by means of a pin 16. The link is pivotally supported at its outer end upon a portion of the frame 10 by means of a pin 17.

The link 15^a has its outer end pivotally supported on a block 18 by means of a pin 19. This block 18 is fixedly attached to a strip 40 of metal 20 which is adapted to extend along the edge portion of the frame 12 forming a portion of the said panel. Screws 21 pass through openings formed in the ends of the strip of metal 20 and threadedly engage into the frame 12 forming 45 the panel for fixedly supporting this strip.

Resilient means is provided for urging the panel against the frame 10 for closing the same and comprises a spring 22 coaxially mounted upon 50 55

the pivot point of the hinges 14 and having one of its ends engaging against the bottom edge of the frame 12 which forms a portion of the panel, and the other of its ends engaging against the 5 outer face of the frame 10 for normally urging the panel into its closed position shown by the dot and dash lines 12' in Fig. 7, and the full lines in Fig. 6.

A finger 23 is rigidly mounted on the link adjacent the panel and comprises a member substantially L-shaped in construction and having one of its arms fixedly attached to the inner end of the link 15^a which is pivotally supported upon the panel. The other arm of the finger 23 is formed with an enlarged head 23^a, in the form of a roller.

A hook 24 is pivotally mounted on the frame 10 and is cooperative with the finger 23 to releasably hold the said finger to hold the panel 20 in its open position. The hook 24 comprises a strip of metal or other similar material which is formed intermediate of its ends with outwardly extending lugs 24^a. A plate 25 is formed at its ends with openings through which screws 26 25 pass for fixedly attaching the plate 25 to a portion of the frame 10. This strip 25 is also formed with outwardly extending lugs 25^a which are adapted to extend along the sides of the lugs 24^a. A pin 26' passes through the lugs 24^a and 30 25^a for pivotally supporting the hook 24 upon the strip 25. The upper end of the strip of metal forming the hook 24 is bent into substantially hook shape 24^b beneath which the enlarged roller head 23^a in the form of a roller of the finger 35 23 is adapted to be engaged for extending the links 15 to hold the panel in its open position.

A clock-controlled means is provided for pivoting the hook 24 to release the finger 23 so that the spring 22 may urge the panel into its 40 closed position with relation to the frame 10. The clock controlled means comprises a clock 27 of conventional construction which is fixedly attached to an arm 25^b extending from the plate 25. The clock 27 is formed with a handle 27^a 45 which is adapted to be rotated for winding the main spring 27^b thereof to cause the clock to operate in the usual manner. The time mechanism has an hour spindle which extends from the front thereof. A dial 28 is mounted on the 50 hour spindle and is formed with a cam 28^a which is adapted to strike against the bottom portion 24^c of the hook 24 for pivoting the hook 24 to release the finger 23. The dial 28 is imprinted with numbers from zero to 11 along its outer 55 edges and which are adapted to be viewed through a window opening 29 formed in a portion of the frame 10.

A knob 30 extends from the end of the hour mechanism and is adapted to be manually rotated for setting the dial 28 to its desired pre-determined positions for controlling the amount of time which must elapse before the cam 28^a will strike the bottom portion 24^c of the hook 24. If it is desired to have nine hours elapse before 65 the panel is closed the knob 30 is rotated until the number 9 on the dial may be viewed through the window opening 29, as shown in Fig. 1. The dial 28 will then be rotated in a direction shown by the arrow 31 in Fig. 4, and after nine 70 hours will reach the dot and dash position 28^b shown in Fig. 4 and pivot the hook 24 as shown by the dot and dash lines 24' in the said Fig. 4. The finger 23 will then be freed by the hook and the spring 22 will urge the panel closed.

75 Glass strips 32 are engaged into brackets 33

which are attached to the edges of the opening in the frame 10. These glass strips are at the ends of the opening in the frame 10, as clearly shown in Fig. 3, and act to prevent rain or snow from getting within the room.

5 The operation of the device is as follows: The knob 30 is rotated until the desired predetermined time is positioned within the opening 29 and the panel is moved to the open position and the enlarged head 23^a is engaged beneath the hook element 24^b of the hook 24. The person then goes to sleep or follows his ordinary routine, and the clock mechanism 27 will rotate the dial and when the predetermined position is reached the cam 28^a will strike the bottom portion 24^c 15 of the hook 24 and pivot the hook to the dot and dash positions 24' shown in Fig. 4 to free the enlarged head 23^a of the finger 23. When this finger is released the spring 22 will urge 20 the panel into its closed position as shown by the full lines in Fig. 6.

According to the modifications shown in Figs. 9-13 a means is provided for adjusting the mechanism to hold the panel open to different degrees. 25 The hook 24 is formed with enlarged elongated lugs 24'' which are formed with elongated slots 40 through which the pin 26' passes. The hook 24 may be moved vertically by shifting the position of the pin 26' within the slot 40 for adjustably supporting the hook 24 upon the plate 25. The elongated slots 40 are formed with aligned offset portions 40^a into which the pin 26' is adapted to engage and about which the hook 24 pivots. A spring 41 has one of its ends bearing against the bottom face of the hook 24 35 for urging the said hook into a position in which the pin 26' will engage the offset portions 40^a of the slots 40.

The finger 23' is rigidly adjustably supported upon the link 15^a so that it may be adjusted 40 with relation to different positions of the links so that the arm upon which the roller head is mounted may always be in the horizontal position so that it may be engaged beneath the hook element 24^b of the hook 24. The enlarged head 45 23'' is threadedly supported upon the end of one of the arms of the finger 23' so that it may be moved along the length thereof to properly engage the hook element 24^b.

The means for rigidly adjustably supporting 50 the finger 23' upon the link 15^a comprises a disc 42 attached to the inner face of the finger 23' and which is adapted to abut an adjacent disc 43 supported on the end of the link 15^a. A pin 44 extends from the disc 43 and passes through 55 openings formed in the disc 42 and the adjacent portion of the finger 23' and is formed at its inner end with an enlarged head 44^a. A spring 45 has one of its ends acting against the finger 23' and the other of its ends acting against the head 44^a for urging the disc 42 against the disc 43. The disc 42 is formed with a serrated portion 42^a which is adapted to engage complementary serrations 43^a formed on the adjacent face of the disc 43. When the serrations 42^a and 43^a 60 are interengaged with each other the finger 23 is rigidly supported upon the link 15^a.

The operation of this form of the device is as follows:

The position of the parts as shown in Fig. 9 70 is similar to that shown in Fig. 7 in which the panel is fully open with relation to the frame 10. When it is desired to have the panel only slightly open with relation to the frame 10 as shown in Fig. 10, the hook 24'' is moved upwards, as shown 75

by the full lines in Fig. 10 and the dot and dash lines in Fig. 11. This is accomplished by pressing inwards on the outer face of the hook 24 to disengage the pin 26' from the offset portions 40^a of the slots 40. The hook 24 may then be moved upwards with relation to the pin 26', and when the pressure is again released the spring 41 will urge the hook 24 into a position in which the lowermost offset portions 40^a will engage the pin 26'. The panel is then opened the desired amount and the finger 23' is adjusted upon the link 15^a so that the enlarged head 23'' will be horizontal with relation to the hook element 24^b. This is accomplished by urging the finger 23' outwards 10 to disengage the serrations 42^a and 43^a so that the finger may be rotated upon the pin 44 to the desired position. The finger is again released and the spring 45 will urge the finger 23' to a position in which the serrations 42^a and 43^a will 15 again be inter-engaged for rigidly supporting the finger upon the link 15^a.

The enlarged head 23" is then moved inwards with relation to the end of the finger 23 so that it will be engaged beneath the hood element 24^b 25 and the device is set for holding the panel open slightly as shown in Fig. 10. The procedure is now similar to that described in connection with the form shown in Figs. 1-8. When the cam 28^a strikes against the bottom portion 24^c of the 30 hook 24 it will release the finger 23' and permit the panel to be closed by the spring 22.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. An automatic self-closing window ventilator, comprising a frame for engagement at a window opening, a panel hingedly mounted at its bottom edge on said frame and capable of extending across said frame to close same, a pair of links pivotally connected at their inner ends and pivotally connected at their outer ends to said panel and frame respectively and adapted to fold closed

45 50 when the panel closes said frame, resilient means for urging the panel against said frame to close same, a finger rigidly adjustably mounted on the link adjacent said panel, a hook pivotally mounted on said frame and cooperative with said finger to releasably hold the finger to hold the panel open, and clock controlled means for pivoting said hook to release said finger so that the resilient means moves said panel to close said frame.

55

2. An automatic self-closing window ventilator, comprising a frame for engagement at a window opening, a panel hingedly mounted at its bottom edge on said frame and capable of extending across said frame to close same, a pair of links pivotally connected at their inner ends and pivotally connected at their outer ends to said panel and frame respectively and adapted to fold closed when the panel closes said frame, resilient means for urging the panel against said frame to close same, a finger rigidly adjustably mounted on the link adjacent said panel, a hook pivotally mounted on said frame and cooperative with said finger to releasably hold the finger to hold the panel open, and clock controlled means for pivoting said hook to release said finger so that the resilient means moves said panel to close said frame,

said finger comprising a piece of substantially L-shaped material having one of its arms rigidly attached to the inner end of the link adjacent said panel, said L-shaped member having the other of its arms formed with an enlarged roller head.

3. An automatic self-closing window ventilator, comprising a frame for engagement at a window opening, a panel hingedly mounted at its bottom edge on said frame and capable of extending across said frame to close same, a pair of links pivotally connected at their inner ends and pivotally connected at their outer ends to said panel and frame respectively and adapted to fold closed when the panel closes said frame, resilient means for urging the panel against said frame to close same, a finger rigidly adjustably mounted on the link adjacent said panel, a hook pivotally mounted on said frame and cooperative with said finger to releasably hold the finger to hold the panel open, and clock controlled means for pivoting said hook to release said finger so that the resilient means moves said panel to close said frame, said finger comprising a piece of substantially L-shaped material having one of its arms rigidly attached to the inner end of the link adjacent said panel, said L-shaped member having the other of its arms formed with an enlarged roller head, said hook comprising a strip of metal being pivotally supported intermediate its ends upon a plate attached to a portion of said frame, said strip of metal having its upper end bent into a hook element beneath which said enlarged roller head of said finger is adapted to be engaged for holding said panel in the open position against the action of said resilient means.

4. An automatic self-closing window ventilator, comprising a frame for engagement at a window opening, a panel hingedly mounted at its bottom edge on said frame and capable of extending across said frame to close same, a pair of links pivotally connected at their inner ends and pivotally connected at their outer ends to said panel and frame respectively and adapted to fold closed when the panel closes said frame, resilient means for urging the panel against said frame to close same, a finger rigidly adjustably mounted on the link adjacent said panel, a hook pivotally mounted on said frame and cooperative with said finger to releasably hold the finger to hold the panel open, and clock controlled means for pivoting said hook to release said finger so that the resilient means moves said panel to close said frame, said finger comprising a piece of substantially L-shaped material having one of its arms rigidly attached to the inner end of the link adjacent said panel, said L-shaped member having the other of its arms formed with an enlarged roller head, said hook comprising a strip of metal being pivotally supported intermediate its ends upon a plate attached to a portion of said frame, said strip of metal having its upper end bent into a hook element beneath which said enlarged roller head of said finger is adapted to be engaged for holding said panel in the open position against the action of said resilient means, said clock controlled means comprising a clock of conventional construction supported upon a portion of said plate supporting said hook, a dial attached to the hour spindle of the time mechanism of said clock, means for setting said dial to predetermined times, and a cam extending from the outer periphery of said dial and adapted to strike the bottom portion of said hook opposite said hook element when said predetermined time is reached 75

for pivoting said hook to release said finger and permit said resilient means to operate.

5. An automatic self-closing window ventilator, comprising a frame for engagement at a window opening, a panel hingedly mounted at its bottom edge on said frame and capable of extending across said frame to close the same, a pair of links pivotally connected at their inner ends and pivotally connected at their outer ends to said panel and frame respectively and adapted to be closed when the panel closes said frame, resilient means for urging the panel against said frame to close the same, a hook pivotally and adjustably mounted on said frame, and a finger rigidly adjustably mounted on said link adjacent said panel and adapted to be adjusted thereon so as to be engaged beneath said hook in all adjusted positions of said hook, and a clock controlled means for pivoting said hook to release said finger so that said resilient means may move said panel to close said frame.

6. An automatic self-closing window ventilator, comprising a frame for engagement at a window opening, a panel hingedly mounted at its bottom edge on said frame and capable of extending across said frame to close the same, a pair of links pivotally connected at their inner ends and pivotally connected at their outer ends to said panel and frame respectively and adapted to be closed when the panel closes said frame, resilient means for urging the panel against the said frame to close the same, a hook pivotally and adjustably mounted on said frame, and a finger rigidly adjustably mounted on said link adjacent said panel and adapted to be adjusted thereon so as to be engaged beneath said hook in all adjusted positions of said hook, and a clock controlled means for pivoting said hook to release said finger so that said resilient means may move said panel to close said frame, said pivotal and adjustable supporting of said hook comprising elongated lugs formed on the sides of said hook and having elongated slots formed therein, a stationarily mounted pin extended through said slots for pivotally supporting said hook, said slots being

formed with aligned offset portions into which said pin is adapted to be selectively engaged for adjustably supporting said hook upon said pin, and means for urging said hook into positions in which said pin will engage said offset portions so that said hook may be moved to various vertical positions for holding said panel open to different degrees.

7. An automatic self-closing window ventilator comprising a frame for engagement at a window opening, a panel hingedly mounted at its bottom edge on said frame and capable of extending across said frame to close the same, a pair of links pivotally connected at their inner ends and pivotally connected at their outer ends to said panel and frame respectively and adapted to be closed when the panel closes said frame, resilient means for urging the panel against said frame to close the same, a hook pivotally and adjustably mounted on said frame, and a finger rigidly adjustably mounted on said link adjacent said panel and adapted to be adjusted thereon so as to be engaged beneath said hook in all adjusted positions of said hook, and a clock controlled means for pivoting said hook to release said finger so that said resilient means may move said panel to close said frame, said pivotal and adjustable supporting of said hook comprising elongated lugs formed on the sides of said hook and having elongated slots formed therein, a stationarily mounted pin extended through said slots for pivotally supporting said hook, said slots being formed with aligned offset portions into which said pin is adapted to be selectively engaged for adjustably supporting said hook upon said pin, and means for urging said hook into positions in which said pin will engage said offset portions so that said hook may be moved to various vertical positions for holding said panel open to different degrees, said latter means comprising a spring attached at one end to a portion of said frame and having the other of its ends engaging against the bottom face of said hook.

EDWARD C. HASSILDINE. 45
